The ornamental design for a hinge portion of an access door, as shown and described.

DESCRIPTION

This application is related to U.S. utility patent application Ser. No. 12,868,931, filed of even date herewith, the entire disclosure of which is incorporated herein by reference.

FIG. 1 is a perspective view of the hinge portion of an access door showing my new design according to a first embodiment;

FIG. 2 is another perspective view of the first embodiment; FIG. 3 is still yet another perspective view of the first embodiment;

FIG. 4 is a front elevational view of the first embodiment; FIG. 5 is a right side elevational view of the first embodiment; FIG. 6 is a left side elevational view of the first embodiment; FIG. 7 is a rear elevational view of the first embodiment; FIG. 8 is a top plan view of the first embodiment; FIG. 9 is a bottom plan view of the first embodiment; FIG. 10 is a sectional view of the first embodiment taken along line 10—10 of FIG. 8; and,

FIG. 11 is a perspective view of the hinge portion of an access door showing my new design according to a second embodiment, the second embodiment being identical to the first embodiment except that the second embodiment has an indeterminate length as indicated in FIG. 11.

The broken lines in FIGS. 1-6 and 8-11 form no part of the claimed design.
